UNITED STATES PATENT OFFICE.

FREDERICK W. SPANGLER, OF CHICAGO, ILLINOIS, ASSIGNOR TO THE MANTLE LAMP COMPANY OF AMERICA, OF CHICAGO, ILLINOIS, A CORPORATION OF ILLINOIS.

WICK CLEANER AND SHAPER.

1,349,010.

Specification of Letters Patent. Patented Aug. 10, 1920.

Application filed June 1, 1918. Serial No. 237,708.

To all whom it may concern:

Be it known that I, FREDERICK W. SPANGLER, citizen of the United States, residing at Chicago, in the county of Cook and 5 State of Illinois, have invented certain new and useful Improvements in Wick Cleaners and Shapers; and I do hereby declare the following to be a full, clear, and exact description of the invention, such as will enable others skilled in the art to which it app pertains to make and use the same.

The invention is a device for cleaning and shaping wicks of the annular type or such as are used in Argand burners. Said invention is especially useful in connection with burners of the non-luminous type which are employed for the heating of light-giving incandescent mantles.

Experience has shown that the successful 20 operation of an incandescent mantle lamp is largely dependent upon the proper trimming and shaping of the lamp wick and the cleaning of the parts adjacent to the wick, and that the lamp users do not take 25 the necessary precautions to properly trim and care for the wick or to clean the parts to which foreign matters have become adherent.

The invention enables the user of a lamp 30 of the above described type to mechanically and accurately trim and shape a lamp wick and at the same time to scrape away any accumulated crusts of carbon deposited on the metal parts of the lamp adjacent to the wick. By the use of this wick trimming device, the wick may be trimmed and sized 35 in such manner as to assume the form and have the condition which in practice have been found the most satisfactory as regards 40 the area of the exposed wick surface, the degree of inclination of said surface and the symmetry of the tip of the wick, all of which qualify the character of the flame of the burner. The device also standardizes the 45 trimming of the wick so that a user can obtain uniform results.

In incandescent mantle lamps, it is desirable to maintain the parts of the burner near the wick free from deposits of carbon 50 which, being absorptive, are liable to undesirably increase the vaporizing surface and consequently evaporation of fuel at certain points in the circumference of the burner, and also interfere with the introduction of 55 air, thereby affecting the shape of the flame.

Experiments have shown that there is a preferred manner of forming or trimming a wick for use in incandescent mantle lamps, and that when such a wick is formed with a slightly sloping or tapered edge, better 60 results are attained than where the wick is given a true transverse cut. Experiments have also shown that it is desirable to form a wick with predetermined inside and outside diameters so that the wick when it is 65 elevated will form a hollow cylinder which is properly spaced from the air admission members of the burner.

The wick cleaner and shaper is so constructed as to mechanically combine with 70 the burner upon which it may be rotated while carrying into effect the cleaning and shaping process, during which the wick is put in perfect condition for use.

Figure 1 is a view in elevation of the invention applied to the upper portion of a 75 burner;

Fig. 2 is a transverse vertical section; and Fig. 3 is a plan view showing the cleaner and shaper from beneath, and Fig. 4 a fragmentary view in elevation.

A is the spacing element of a lamp and B the upper section of the outer wick tube which is carried thereby. b is what is known as a flame flange encircling the upper end of the wick tube section B.

C is the inner wick tube and D the wick of the burner.

E is the improved cleaner and shaper and F its knurled cap which encircles and is secured to the body of the cleaner and shaper by indentations x. The device has a tubular body e of cylindrical form, from which is cut and bent blades e' having at their ends flanges e² carrying downwardly 95 deflected scraping edges, y, which rest upon the flame flange b. The cap F is provided with a cylindrical body f, the lower edge thereof carrying downwardly extending arms f' the ends of which bear upon the flanges e², so as to hold said ends in true 100 position. The arms f' are provided with strengthening ribs f² extending lengthwise thereof.

The tubular body e is provided with a shoulder e³ in which the upper portion of said tubular body originates. Said tubular body fits loosely in the inner wick tube and by virtue of the lateral displacement of its upper portion fits also the annular wick and 110

thereby prevents inward displacement of any parts of the wick during the cleaning and shaping operation. The blades are co-extensive in length with the exposed portion 5 of the wick and the flanges e^2 are in length equal to the width of the flame flange b . The wick therefore during the cleaning and shaping operation is supported on its inside by the tubular body e , the result being that 10 the cleaning and shaping operation of the blades e' effectuates no undesirable distortion. These blades during the operation of the device travel around the flame flange b upon which their flanges e^2 rest. The result 15 of the operation is the production of a wick tip of perfectly circular form, and one which is free from any fibrous projections. The end of the wick takes the shape of the blades e' which as already 20 stated are formed from a bent portion of the tubular body e , the curvature of said arms determining the exact shape of the tip of the wick. The several arms all follow 25 in the same path being sustained by their flanges e^2 which rest upon the flame flange b and are held from upward displacement by the arms f' .

The parts of the device are preferably stamped from sheet metal, although it will 30 be understood they may be produced in any other manner.

Having thus described my invention, what I claim is:

1. A wick cleaner and shaper having a 35 tubular portion or body and inclined blades for beveling a wick extending laterally therefrom and terminating below their points of origin, and means adapted to co-operate with the outer wick tube of a burner 40 for limiting the descent of said cleaner in a wick tube, said points of origin being disposed above said means.

2. A revoluble wick cleaner and shaper 45 for a tubular wick, having a cylindrical body the upper portion of which conforms to the inside of the wick to thereby sustain and maintain the shape thereof during the trimming operation, and provided with downwardly deflected trimming and shaping 50 blades for removing incrustations from and uniformly beveling the exterior of the wick.

3. A wick cleaner and shaper having a 55 tubular portion or body and curved blades extending outward and downward therefrom, said blades being provided at their ends with outwardly extending horizontal flanges.

4. A wick cleaner and shaper having a 60 tubular portion or body, blades extending laterally therefrom and terminating below their points of origin, and reinforcing arms for said blades.

5. A wick cleaner and shaper having a 65 tubular portion or body, a cap for said body,

blades extending outward and downward 65 from said portion or body and reinforcing arms for said blades carried by said cap.

6. A wick cleaner and shaper having a cylindrical body portion, the lower end of which is adapted to fit within the inner wick 70 tube of a burner, and the upper portion of which is cylindrical and enlarged and adapted to fit within the upper portion of the wick, said cleaner and shaper being provided with outwardly and downwardly extending 75 blades having a desired curvature.

7. The combination with a burner having a circular wick tube, of a wick cleaner and shaper therefor, said cleaner and shaper having a tubular body fitting within the inner wick tube of the burner in which it may turn and being provided with inclined curved blades for externally beveling and with an enlarged portion for internally shaping 80 the wick.

8. A wick cleaner having a lower body portion adapted to fit into a wick tube and an upper body portion of greater diameter than the lower body portion, said upper portion being adapted to form the inside 90 diameter of the wick to a predetermined size.

9. A wick cleaner and shaper including a tubular body portion, a cap telescoping therewith, outwardly and downwardly extending blades originating in said tubular body portion, and reinforcing arms for said blades originating in said cap.

10. A rotary wick cleaner and shaper, including means for beveling and shaping an 100 annular wick, and additional means for scraping adjacent metal parts of the burner.

11. A rotary wick shaper, including blades for beveling the tip of an annular wick, said blades having each a terminal 105 supporting flange.

12. A wick cleaner and shaper having a trimming blade for operating upon a wick, and means adapted to rest on the flange of an outer wick tube for sustaining and causing said trimming blade to operate above the top of a wick tube during the trimming 110 operation.

13. A rotary wick cleaner and shaper, including means extending over an exposed tip of a wick to size the interior of a wick and bevel its tip, said means conforming to the curvature of the inner wall of the wick.

14. A wick cleaner and shaper having a tubular body portion and a wick-trimming blade extending laterally therefrom and terminating below its point of origin, said blade terminating in a downwardly deflected scraping edge for cleaning the upper end of a wick tube.

In testimony whereof I affix my signature.

FREDERICK W. SPANGLER.
